R. H. Macy & Co. Inc., New York, N. Y., a corporation of New York

Application September 29, 1942, Serial No. 460,061

5 Claims. (Cl. 155—179)

This invention relates to furniture such as chairs, divans and sofas and has for its object the provision of an improved spring construction for both seat and back.

It has been the general practice to use steel coil springs in the seat platform and back of upholstered furniture to give the yielding support required for comfort. Although such springs perform their function admirably they must be securely tied in place at the cost of much tedious labor, which adds to the cost of the furniture and so is objectionable. Hence a substitute would be desirable for reasons of economy. There is, however, a more compelling reason for developing a substitute for the steel spring: there is—or soon will be—no more steel available for upholstery springs. Steel springs have gone to war.

This being the situation facing upholsterers, I have invented a satisfactory substitute for the steel springs used in upholstered furniture. I have devised a spring construction in which wood can be, and is, used as the resilient element. My construction is such that were steel available it could be used, but the great present virtue of my invention is that it enables me to produce a quite satisfactory and comfortable piece of upholstered furniture without an ounce of spring steel in the whole of it.

The best way to explain what I have done is to describe the chair embodying my invention that is illustrated in the drawings accompanying this application.

In these drawings Figure 1 is a vertical longitudinal section through an upholstered chair embodying my invention; Figure 2 is a horizontal section taken along line 2—2 of Figure 1; Figure 3 is a detail on an enlarged scale showing one method of securing the forward end of one of the seat springs to the frame of the chair; Figure 4 illustrates an alternative method of fixing the forward end of the seat spring; Figure 5 is a horizontal section taken along line 5—5 of Figure 1; Figure 6 is a detail showing one method of holding the back springs in position; and Figure 7 is a view similar to Figure 1 showing a modified form of seat spring construction.

The chair illustrated in these drawings comprises the usual frame 1 which supports a seat platform 2 and a back 3. I shall first describe the seat platform construction of my invention and then describe the construction of the back.

My spring elements comprise two strips of wood 4 bowed as illustrated in Figure 1. These strips may be made either of solid wood or they

may be in the form of laminated veneer strips glued together. In either case the strips are bent to conform to the desired curvature and are tough and resilient. The forward end of each strip 4 is fixed to the inner side of the front rail of the chair at 5 and the rear ends are attached to a transverse bar 6 which acts as the back rail of the platform 2 and which is not otherwise attached to the chair frame. A webbing 7 of duck, burlap or other suitable material which constitutes the base of the platform is attached to this back rail 6 and to the front rail at 8. The webbing 7 is drawn taut and, being inextensible, tends to hold the wood strips 4 in the bent position shown in Figure 1. A cross-bar 9 having a downwardly and rearwardly sloping face, as shown in Figure 1, is mounted transversely of the frame and supports the strips 4 at its forward and upper end. The upper face of the cross-bar 9 is, in effect, tangent to the curvature of the strips. The webbing 7 is provided with the usual covering comprising a web of burlap 10 stretched and tacked to the four rails of the chair frame and over this is added the usual thin layer of stuffing 11 which, in turn, is covered by a fabric 12.

As shown in Figures 1 and 3, the inner face of the front rail on the chair frame is provided with two downwardly and backwardly sloping slots 13 of proper size to receive the forward ends of the strips 4. In order to make a snug fit and to eliminate creaking, the forward end of each slot is provided with a lining of felt 14. A dowel pin 15 extends through each strip at right angles to it and into the forward rail. A modified construction is shown in Figure 4. Here a separate rail portion 16 is screwed to the frame and the strip is screwed to it. As illustrated in Figure 1 the rear ends of the strips 4 lie upon shoulders 17 in the floating back rail 6, which is covered with a layer of felt 18. The upper face of the cross-bar 9 is also covered with felt 19 under the strips 4. It is possible to eliminate those parts of the strips forward of the cross-bar and secure the forward ends of the shortened strips at the upper edge of the cross-bar itself. Supported upon the seat platform 2 is a stuffed cushion 20 which may be made of sponge rubber or any other suitable soft and resilient material.

The weight of a person sitting in the chair just described is concentrated somewhat to the rear of the center of the platform. The application of this weight deforms the platform and its supporting springs, as follows: The webbing 7, which

carries the weight, is bowed downwardly and deflected out of its normal straight line position between the front rail and the floating back rail. This results in pulling the rear ends of the wood strips 4 and the rail 6 forwardly. At the same time the strips 4 are swung downwardly from the fulcrum point at the upper forward edge of the cross-bar 9, and this results in a lowering of the back rail. As the strips 4 are bent downwardly, they are flattened along the declining face of the cross-bar 9, the point of contact moving down the face of the bar, shortening the effective length of each wooden spring and increasing its bending resistance until equilibrium is reached (provided the weight of the person does not exceed the strength of the strips 4 to support it). The downward bowing or bellying of the webbing 7 provides a form-fitting support for the person and the progression of the point of tangency, along the cross-bar 9, automatically stiffens the spring resistance of the strips 4 to compensate for increasing weights. Thus, for a light person the effective length of the strips 4 is greater than for a heavy person. The strips 4 are sufficiently stiff to prevent bottoming of the platform web under any weight that the chair is capable of supporting, so that a resilient and springy support is provided at all times. When pressure on the platform is relieved, the strips 4 spring back to their original positions, holding the webbing 7 taut, and free from sag.

The back of the chair comprises a series of vertical wooden strips 21 similar to the strips 4, but narrower in width. These strips are firmly anchored at their lower ends to a cross-bar 22 and extend upwardly, first curving outwardly and then curving inwardly along a smooth curve. The upper ends of the strips 21 lie against a pad 23 but are not fastened to it. They are held in place by means of two pieces of burlap 24 sewed together to form channel pockets 25 for receiving them, the web 24 being tacked to the sides of the back frame. Interlacing strips of burlap, duck or similar material might also be used. A strip of some fabric 26 overlies the strips 21, fastened at its lower end to the cross-bar 22 and at its upper end to the back frame at 27, just in rear of the pad 23. The fabric 26 is so shaped at its upper end as to afford room for vertical play of the strips 21. The back is covered with any suitable soft stuffing 28 held within an outer fabric cover 29 and brought around the top of the back frame in the conventional manner.

When a person sitting in the chair leans against the back, the strips 21 afford a yielding support. The pressure against the strips 21 tends to flatten them, which causes the over-all length between the ends of the strips to increase, resulting in a sliding movement of the upper ends along the pad 23. By anchoring the strips 21 at their lower ends while leaving them free at their tops, and supported against a yielding pad, a firm support for the back is afforded in the vicinity of the kidneys without sacrificing a comfortable resiliency where it is needed. As the strips are independently mounted, each may flex separately, and thus the back can adapt itself to the form of the sitter.

In the modified form shown in Figure 7, the front rail is provided with a floating section 30 supported by short wooden spring strips 31 anchored to the cross-bar 9. As the strips 31 carry

a much lighter load than the strips 4, they need be only half the width of the latter. The webbing 7 is secured at the front to a fixed front rail and at the back to the floating back rail. As it lies below the floating front rail, the strips 31 pass upwardly between sections of the webbing. Except for the fact that some resiliency is afforded at the front rail by this construction, the operation is precisely the same as that of the structure shown in Figure 1. A single strip 4 may be employed extending from the front to the back rail, but it is preferable to employ separate strips.

I have illustrated two spring strips in the seat 15 of the chair because I have found that number satisfactory. This number can, of course, be changed. I have illustrated my invention embodied in an upholstered chair and have so described it, but it is clear that the principles involved are equally applicable to divans, sofas, 20 benches, davenports and other seats, whether upholstered or not, and the word chair, as used in the claims, is intended to include all such functionally equivalent furniture.

25 1. A chair comprising a frame, a front rail, a floating back rail, flexible, inextensible webbing connecting the two, a downwardly bowed strip spring secured at its forward end to the front rail and at its rearward end to the back rail, and a cross-bar carried by the frame between and below the two rails and supporting the spring tangentially.

30 2. A chair comprising a frame, a front rail, a floating back rail, flexible, inextensible webbing connecting the two, a downwardly bowed strip of resilient wood secured at its forward end to the front rail and at its rearward end to the back rail, and a downwardly and rearwardly sloping cross-bar carried by the frame between and below the two rails and supporting the wooden strip tangentially.

35 3. A chair comprising a frame, a front rail, a floating back rail, flexible, inextensible webbing connecting the two, a downwardly bowed strip of resilient wood secured at its forward end to the front rail and at its rearward end to the back rail, and a downwardly and rearwardly sloping cross-bar carried by the frame forward of its 40 middle between and below the two rails and supporting the wooden strip tangentially near its upper edge when the chair is unoccupied, and over a progressively wider area of its upper surface as the load carried by the chair is increased.

45 4. A chair comprising a frame, a front rail, a floating back rail, a platform supported by the two rails, a downwardly bowed strip spring secured at its forward end to the front rail and at its rearward end to the back rail, and a cross-bar carried by the frame between and below the two rails and supporting the spring tangentially.

50 5. A chair comprising a frame, a front rail, a floating back rail, a platform supported by the two rails, a downwardly bowed strip of resilient wood secured at its forward end to the front rail and at its rearward end to the back rail, and a cross-bar carried by the frame forward of its middle between and below the two rails and supporting the wooden strip tangentially near its forward edge when the chair is unoccupied, and over a progressively wider area of its upper surface as the load carried by the chair is increased.
